CLAIM

The ornamental design for a latch, as shown and described.

DESCRIPTION

FIG. 1 is perspective view of a latch embodying our design; FIG. 2 is a right side elevational view of the latch in FIG. 1, the left side being a mirror image of that shown; FIG. 3 is front elevational view of the latch of FIG. 1; FIG. 4 is a rear elevational view of the latch of FIG. 1; FIG. 5 is a top plan view of the latch of FIG. 1; FIG. 6 is a bottom plan view of the latch of FIG. 1; and, FIG. 7 is a perspective view of the latch of FIG. 1 in a closed position.

The broken lines showing a portion of a latch in FIGS. 1-7 are for illustrative purposes only and form no part of the claimed design.
